UNITED STATES PATENT OFFICE.

ANDREW ANDERSON, OF BINGHAM CANYON, UTAH, ASSIGNOR OF ONE-HALF TO
CHARLES NYGORD, OF BINGHAM CANYON, UTAH.

PEN-POINT RELEASER.

1,060,561.

Specification of Letters Patent.

Patented Apr. 29, 1913.

Application filed June 1, 1912. Serial No. 701,013.

To all whom it may concern:

Be it known that I, ANDREW ANDERSON, a citizen of the United States, residing at Bingham Canyon, in the county of Salt Lake and State of Utah, have invented certain new and useful Improvements in Pen-Point Releasers, of which the following is a specification, reference being had therein to the accompanying drawing.

10 This invention relates to pen holders and has for its object the production of an efficient pen-point-retaining-clamp and means for holding said clamp in engagement with said holder.

15 Another object of this invention is the production of a pen holder provided with a retaining-socket adapted to hold the pen-point-retaining-clamp in engagement with said holder.

20 With these and other objects in view this invention consists in certain novel combinations, constructions, and arrangement of parts as will be hereinafter fully described and claimed.

25 In the accompanying drawings:—Figure 1 is a side elevation of the device showing the casing in section. Fig. 2 is a central longitudinal section of the device. Fig. 3 is a section taken on line 3—3, of Fig. 1. Fig. 4 is a section on line 4—4, of Fig. 1. Fig. 5 is a detail perspective of the pen holder. Fig. 6 is a view which discloses the spring which partially encircles the coil spring.

30 Referring to the accompanying drawings 35 1 designates a pen holder which is provided with a pen-point-retaining-clamp-receiving-socket 2 in which the pen-point-retaining-clamp 3 fits. The receiving-socket 2 is provided with the abutting shoulder 4, which 40 is adapted to prevent any longitudinal movement of the pen-point-retaining-clamp 3 after the same has been placed within the receiving-socket 2. The outer end of the pen holder 1 is provided with the upstanding portion 5. This upstanding portion 5 is provided with a reduced portion 6 adapted to receive the pen-point-retaining band or collar 7. Centrally located upon the upper face of the upstanding portion 5 is positioned a pen-point-retaining-rib 8. It will be seen that by use of a pen-point-retaining-collar and the pen-point-retaining-rib the pen is held in a firm engagement with the holder independently of the pen-point-re-

taining-clamp. Positioned upon the inner 55 end of the receiving-socket 2 is a shoulder 9, which is adapted to limit the inward movement of the pen-point-retaining-clamp 3 and to act as a supporting means for the metallic casing 10.

60 A pen-point-retaining-clamp 3 is positioned within the receiving-socket 2 and is composed of a plurality of clamping portions 11. The clamping portions 11 are provided on their outer ends with the laterally 65 extending gripping jaws 12, which rest against the shoulder 4. It will be seen that when the clamp is in this position these gripping jaws prevent the retaining-clamp from coming out as well as forming an efficient means for retaining the pen point. The clamping portions 11 are pivotally mounted upon the journal pin 13 and are adapted to be operated by means of the operating lug 14, which passes through the 70 aperture 15 formed in the casing 10. A coil spring 16 is carried by the journal pin 13 and normally holds the gripping jaws 12 in engagement with the pen point. Positioned on the inner side of the pen-point-retaining-clamp is a secondary flat 75 spring 18, which partially encircles the coil spring 16 and forms a secondary spring member. Positioned near the outer end of the pen-point-retaining-clamp are a plurality of pen-point-engaging pads 19. It will be seen that if the edges of the gripping jaws should become worn the clamping portions will hold the pads 19 in engagement with the pen point and in this manner 80 form a gripping means independently of the gripping jaws. A metallic casing 10 is positioned upon the lower end of the pen holder 1 and is especially adapted to hold the pen-point-retaining-clamp 3 in its correct position in the receiving-socket 2.

85 By referring to Fig. 5 it will be seen that the pen holder is provided with a receiving-socket adapted to hold the pen-point-retaining-clamp in such a position as to eliminate 90 any longitudinal movement thereof, as well as the production of an efficient gripping means to coöperate with the retaining-clamp. It is further obvious that the retaining-clamp is of a very simple construction and is provided with a primary and secondary gripping means formed near its outer end.

Having thus described the invention what is claimed as new, is:—

A pen holder of the class described, provided near its outer end with a longitudinally extending receiving-socket, an upstanding portion formed adjacent said receiving-socket, said upstanding portion provided with a pen-point-retaining rib, a reduced portion formed upon the outer end 10 of said upstanding portion, a collar carried by said reduced end, a pen-point-retaining-clamp mounted within said receiving-socket, said retaining-clamp comprising a plurality of clamping portions, the outer 15 ends of which are bent to form laterally extending gripping jaws abutting against the inner face of said upstanding portion and adapted to prevent any longitudinal movement of the retaining-clamp, pen-point-engaging-pads positioned within said clamping portions and adapted to hold the pen point in its correct position independently 20

of the gripping jaws, a journal pin carried by said retaining-clamp, a coil spring mounted upon said journal pin and adapted to hold the outer end of said retaining-clamp in a closed position, a secondary flat spring carried within said retaining-clamp and partially encircling said coil spring, an operating lug carried by one portion of 30 said retaining-clamp, said lug being adapted to compress the inner portions of said retaining-clamp when it is desired to eject the pen point, and a casing carried by the outer end of said pen holder, said casing being 35 adapted to hold the retaining-clamp in its correct position in the receiving-socket.

In testimony whereof I hereunto affix my signature in presence of two witnesses.

ANDREW ANDERSON.
